Primary Examiner — Keli L Hill*Assistant Examiner* — Harold E Blackwell, II(74) *Attorney, Agent, or Firm* — Mehrman Law Office; Michael J. Mehrman(57) **CLAIM**

The ornamental design for a dowel basket, shown and described herein.

DESCRIPTION

FIG. 1 is a perspective view of a dowel basket, showing the new design;

FIG. 2 is a top view thereof;

FIG. 3 is a side elevational view thereof; and,

FIG. 4 is an end elevational view thereof.

The left and right side elevational views are substantially identical. The broken line portion of the figure drawings is included to show portions of the article that form no part of the claimed design.

1 Claim, 2 Drawing Sheets(56)
